UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

SHADE-HOLDER.

1,106,254.

Specification of Letters Patent. Patented Aug. 4, 1914.

Application filed December 19, 1913. Serial No. 807,752.

To all whom it may concern:

Be it known that I, GEORGE B. THOMAS, a citizen of the United States of America, and residing at Bridgeport, in the county of 5 Fairfield and State of Connecticut, have invented a certain new and useful Improvement in Shade-Holders, of which the following is a specification.

My invention relates to shade holders and 10 particularly to shade holders for electric lamp sockets, the object of my invention being to provide a combined shade holder and socket casing of new and improved construction.

15 In the accompanying drawing, Figure 1 is a dropped elevation partially broken away, of the casing and shade holder elements; Fig. 2 is a side elevation of the casing elements assembled, and Fig. 3 is a vertical section therethrough.

In the form here shown, the present fitting comprises a cap 10 of common construction having a nipple 11 with bail 12 by means of which it may be readily hung from 25 a suspension chain. The nipple may have any desired means however for securing the fitting to its support. The flange 13 of the cap may be provided with any suitable latching means. The apertures 14 here shown are of the type fully described in the 30 Goodridge Patent 958,626.

Sleeving into the cap I provide a member 15 of any suitable shape, here bell-shaped, and provided at its upper edge with latching elements 16 and 17 adapted to engage the latching elements on the cap in substantially any relative rotary position of the parts, and at its lower edge with means for engaging a shade. In the form here shown 40 a spring wire 18 of common type is illustrated, having a bearing loop 19, and finger grips 20, passing through and supported in the lower portion of the bell 15.

To support the electric lamp socket and 45 form an inclosing casing for the lamp receiving end of the latter, I provide a shell 21, shouldered at 22 to take beneath the porcelain body 23 of the socket. This shell may be secured to the bell 15 in any suitable 50 manner. I have here shown a series of semi-circular apertures 24, the straight or engaging edges 25 of which are uppermost, and overlie, in assembled position, the upper edges of corresponding inwardly-pressed

semi-circular bumps 26 on the bell 15. Adjacent these apertures 24 the shell is slit, as at 27 to permit the metal to spring in at these points during the latching action. Preferably these slits 27 are located to the right of the apertures 24 so that the shell is 60 attached by inserting and turning to the right after the fashion of a right handed screw. The engagement may be effected however by a straight inward push of the shell, since the slits 27 permit the shell to 65 yield sufficiently to ride over the bumps 26 which thereupon snap into the apertures 24 without rotation. To separate the parts, it is necessary to turn the shell slightly to the left whereupon the portion of the shell be- 70 tween the apertures 24 and the slit 27 is pressed inward by the bumps 26 which ride up thereon. A recess 29 is preferably formed in the shell to accommodate the switch key 30 (or chain bell in the case of a 75 pull socket).

Inasmuch as the shell 21 reinforces the upper portion of the bell, it is desirable to locate one of the slits 27 adjacent the slit 31 in the bell which not only accommodates 80 the key 30 (or chain bell) but also weakens the bell at this point so that it may be readily pressed in by the fingers to free the latching elements as explained in the Goodridge patent above mentioned. While the 85 shell 21 does not extend into the sleeved area of cap and bell, it underlies the latter at the point at which pressure must be applied, and for this reason it is desirable, in order to minimize the pressure required, 90 that one of the slits 27 in the shell should be adjacent the slit 31 in the upper portion of the bell.

Various modifications of the construction will readily suggest themselves and I do 95 not limit my invention to the details shown.

I claim as my invention:—

1. A fitting of the type described comprising a cap, a shade holder, means for latching the latter to the cap in substantially 100 any relative rotary position of the parts, a socket shell and means for latching the latter to the shade holder against endwise separation of the parts.

2. A fitting of the type described comprising a cap, a shade holder leaving at its 105 upper portion with the cap, means within the sleeved area for latching the shade

- holder to the cap, a socket shell and means lying outside said sleeved area for latching said shell to the shade holder.
3. A fitting of the type described comprising a cap, a bell-shaped shade holder having its upper portion sleeving with the cap, latching means within the sleeved area for latching the shade holder to the cap, a socket shell and means lying outside said sleeved area for latching said shell to the shade holder.
4. A fitting of the type described comprising a cap, a shade holder, means for latching the latter to the cap in substantially any relative rotary position of the parts, a socket shell inwardly shouldered to engage and support the body of a lamp socket and means for latching said shell to the shade holder.
5. A fitting of the type described comprising a cap, a shade holder latching therewith in substantially any relative rotary position of the parts, and means carried by said shade holder for supporting the body of a lamp socket.
6. A fitting of the type described comprising a cap, a shade holder latching therewith in substantially any relative rotary position of the parts, and means carried by said shade holder for supporting the body of a lamp socket.

in substantially any relative rotary position of the parts, and readily detachable means carried by said shade holder for supporting 3 the body of a lamp socket.

7. A fitting of the type described comprising a cap, a shade holder latching therewith in substantially any relative rotary position of the parts, and means carried by said shade holder for supporting and inclosing 35 the lamp receiving end of a lamp socket.

8. A fitting of the type described comprising a cap, a shade holder latching therewith in substantially any relative rotary position 40 of the parts, a socket shell latched to said shade holder, said shell and shade holder being weakened at substantially the same point to facilitate flexion of the shade holder at a point of engagement with the 45 cap.

In testimony whereof I have signed my name to this specification, in the presence of two subscribing witnesses.

GEOERGE B. THOMAS.
